UNITED STATES PATENT OFFICE.

FRANK J. LAHER, OF PORTLAND, OREGON.

DESIGN FOR AN END FITTING FOR VEHICLE BUMPERS.

Application filed June 29, 1925. Serial No. 13,944. Term of patent 3½ years.

To all whom it may concern:

Be it known that I, FRANK J. LAHER, a citizen of the United States, residing at Portland, county of Multnomah, and State of Oregon, have invented a new, original, and ornamental Design for End Fitting for Vehicle Bumpers, of which the following is a specification, reference being had to the accompanying drawing, forming a part thereof.

In the drawing:

Fig. 1 is an elevation of an end fitting showing my new design; and

Fig. 2 is a plan view thereof.

I claim:

The ornamental design for an end fitting for vehicle bumpers as shown.

FRANK J. LAHER.
